SMOKING PIPE

Oscar Stein, Bronx, N. Y.

Application February 21, 1948, Serial No. 10,080

1 Claim. (Cl. 131—184)

1

This invention relates to new and useful improvements in smoking pipes.

According to the invention, a smoking pipe is provided which comprises a main hollow structure cross-shaped or cruciform in side elevation and channelled horizontally and vertically, with these channels crossing each other intermediate the ends of both, thus forming horizontal and vertical channelled extensions, in such manner that one of the horizontally channelled extensions acts as a stummel or bit-mounting member, the upper vertically channelled extension provides a mount for a detachable bowl, the other horizontally channelled extension provides a normal mount for a detachable device for serving, while thus mounted, one of a plurality of special purposes, and the other vertically channelled extension provides at the bottom of said main structure a normal mount for another detachable device having a special purpose while thus mounted.

The first named detachable device, which includes a closure for the main structure opposite the bit carrying end thereof, also includes a rod so fixed to said closure that with the latter normally mounted as above, that is, during smoking of the pipe, the rod extends through substantially the entirety of the horizontal channel through said main structure; whereby there will be condensed or otherwise collected or trapped on the rod the tobacco-oil and the tar-like viscous substances which during pipe smoking gradually accumulate in an ordinary pipe below the bowl. As is well-known by pipe smokers, these accumulations, if left to themselves, sooner or later interfere with easy and free draw on the smoke, badly clog the pipe, result in the delivery of bitter juices to the mouth of the smoker, and generally make the pipe malodorous.

As is also well-known in the smoking pipe art, a fairly small port is employed to afford communication between the bottom of the bowl and the ordinary stummel, and this port is apt frequently to become choked by a piece or particle of tobacco. According to the invention, this trouble is able to be easily and instantaneously overcome, by use of the rod aforesaid, and, very importantly, by driving the tobacco-choke at the bottom of the bowl, not down into the ordinary stummel as heretofore, but upward from the said port and so upward into the bowl.

To perform this operation, it is merely necessary temporarily to detach the second-named detachable device from its normal mounting at the bottom of said main structure, for which bottom

2

said device is normally a closure, and then, through the bottom opening thereby provided, to extend the rod vertically upward into the vertical channel. Since said vertical channel is in line with the smoke-passing port in the bottom of the bowl, said rod may be inserted not only through the entirety of said vertical channel, but beyond the top thereof and into the bowl through the bottom port of the latter.

10 Incidental to each such bowl-clearing operation, naturally the smoker will be reminded to wipe the rod clean from its obnoxious accumulations; and incidental to each removal of the rod for the purpose just noted, naturally the smoker will be reminded to use the rod for bowl-clearing.

The second-named device, removable as above to allow use of the rod for bowl-clearing pursuant to the invention, may be cup-like in nature, thereby, when in place on the main structure, serving as a saliva trap, in and of itself, or through the medium of a contained and discardable cartridge or plucked-wad of compressed or matted raw cotton or the like.

25 A further feature of the invention, as the same is preferably carried out, is to make said main structure of metal, for quick radiation of excessive heat, thereby to provide a cool as well as a clean and sweet smoke. The radiation area of said structure, due to its cruciform shape, is quite large, and the consequent loss of heat by radiation is notably advantageous.

Another feature of the invention is the use of 30 a connector means of the bayonet-joint type, for detachably coupling the bowl to said main structure, and at other places, as for detachably coupling the rod-carrying device to the main structure, and for detachably coupling a bowl-liner to and within the bowl.

In the connection last noted, another feature 40 of the invention is the provision of a liner-bowl, of porcelain, pottery or the like, in combination with a bayonet-joint type of means for detachably connecting such a bowl-liner to and within a main bowl of another material, as one of wood.

45 For further comprehension of the invention, and of the objects and advantages thereof, reference will be had to the following description and accompanying drawing, and to the appended 50 claim in which the various novel features of the invention are more particularly set forth.

In the accompanying drawing forming a material part of this disclosure:

55 Fig. 1 shows an embodiment of the invention, as now favored, in side elevation.

Fig. 2 is a longitudinal vertical section through the same; with, however, a chain elsewhere shown omitted.

Fig. 3 is a view similar to Fig. 1, but showing a rearrangement of the parts for bowl-clearing.

Fig. 4 is a transverse vertical section, taken on the line 4—4 of Fig. 3.

Fig. 5 is a fragmentary side elevation, partially broken away and partially in section, showing a coupling means between the bowl and the main structure which is of screw-thread type rather than of bayonet-joint type.

Fig. 6 is a view similar to Fig. 2, showing another now favored embodiment.

Fig. 7 shows in perspective one of the parts of 15 the pipe shown in Fig. 6.

Referring to the drawing more in detail, 18 designates the aforesaid main structure, cruciform in side elevation, having an upward extension 11, a depending extension 12, a forward extension 14 and a rearward extension 15. A horizontal channel 16 open at both ends passes longitudinally through the structure 10. Intermediate the ends of the channel 16 the same is intersected by a vertical channel, thereby to have the last-mentioned channel provide an upper chamber 17 and a lower chamber 18. These chambers are centered below the bowl 19.

The main structure 10 is desirably of metal, and may be in the form of a single casting, suitably machined.

The forward extension 14 has the function of the stummel of an ordinary pipe, for detachably carrying a bit 20. The bit 20 is shown in Fig. 2 as frictionally gripped at its reduced end 30^a in the extension 14, but as will be understood there may be here a screw-threaded or any other suitable connection.

The rod aforesaid is marked 21, and the same is rigidly carried by a cap 22 having a cylindrical skirt 22^a for detachably sleeving the extension 15. These parts are also desirably of metal. Normally, the rod 21 extends through the channel 16 as in Fig. 2, with the cap 22 closing the extension 15 in an airtight manner.

The bottom of the extension 12 is normally closed by a removable cup 23 having a cylindrical skirt 23^a for entering the lower portion of the chamber 18 within the extension 12 and then abutting a shoulder 24 in said chamber. The cup 23 is also desirably of metal. The cup 23, even when temporarily disconnected from the structure 10 as in Figs. 3 and 4, is held captive by a flexible element, as a chain 25; said chain attached at one end to an apertured lug 23^b projected from the cup 23 and attached at its other end to an apertured ear 26 on the structure 10.

The securement of the cup 23 to the extension 12 for normally closing the bottom of the latter may be by frictional grip, or by way of a screw-thread type of connection, or otherwise, as, for instance, by way of a bayonet-type of connection (not shown) but such as illustrated and below described in connection with the cup 22, the bowl 19, and a bowl-liner 27—which bowl-liner, desirably made of porcelain, pottery or the like, is desirably present. For assistance in manually applying a turning force to the cup 23, in attaching or detaching the same, said cup is illustrated as having a plurality of short outwardly and 70 downwardly inclined fingers 28, spaced around the cup 120° apart.

The cup 23 provided with the skirt 23^a may be employed as a saliva trap, and in that connection a cartridge or plucked-wad 28 of compressed

or matted raw cotton or the like may be deposited in such cup, for replacement when fouled.

Referring to the illustrated connecting means between the cap 22 and the extension 15, which cap is shown as circumferentially knurled beyond the skirt 22^a, said connecting means is shown as comprising a pair of oppositely located bayonet joints each including an L-shaped slot 30 through the skirt 22^a of the cap 22 and a coacting pin 31 offset from the extension 15; one of such slots and its pin being shown in Fig. 1.

A similar connecting means is illustrated as provided for the bowl 19 and the extension 11; the bowl having a depending neck for entering the upper end of the chamber 17 and for resting at its bottom on a shoulder 32 in said chamber. This connecting means is shown as comprising a pair of oppositely located bayonet joints each including an L-shaped slot 33 through said neck of the bowl and a pair of coacting pins 34 carried at the upper end of the extension 11 and inwardly offset therefrom above the shoulder 32.

In regard to the bowl-liner 27, which is shown only in connection with the embodiment of Figs. 1—4, but which may also be present in the form of the invention shown in Fig. 5, this is readily detachable, as for cleaning, close inspection or replacement; and the same is shown as secured within the bowl 19 also by a bayonet-joint connection, such connection comprising a pair of L-shaped slots 35 through the bowl-liner at its upper end and a pair of coacting pins 36 carried by the bowl 19 and inwardly projected therefrom. The bowl-liner has a central bottom smoke passage port 37.

While the pipe is being smoked, the parts are arranged as in Fig. 2. Then the tobacco-oil and viscous matters aforesaid are accumulated on the rod 21, and deposits of saliva drop into the lower portion of the chamber 18 in the extension 12 for reception in the cupped portion presented by the skirt 23^a of the cup 23. For cleaning the rod, the same is withdrawn from the channel 16 following detachment of the cap 22. For cleaning out the saliva, and for renewing the element 28 when advisable, the cap 22 is detached.

In order to eject from the port 37 of the bowl-liner 27 a choking or clogging tobacco piece or particle therein, it is merely necessary to employ the rod 21 as shown in Figs. 3 and 4; that is, first to disconnect the cup 23 and allow the same to dangle from the chain 25, and then, using the cap 22 as a handle, to insert the rod 21 upwardly through the chambers 18 and 17 and then through the port 37 and into the bowl-liner 27. As will be noted from Fig. 4, the external diameter of the skirt 22^a of the cap 22 matches the internal diameter of the lower part of the chamber 18; whereas, as appears in Fig. 2, the internal diameter of the skirt 22^a matches the external diameter of the extension 15.

Referring to the form of the invention shown in Fig. 5, the parts here shown and to which reference characters with primes are applied correspond to the parts of Figs. 1—4 to which reference characters without primes are applied. In the arrangement of Fig. 5, the upper portion of the chamber 17' is internally threaded, and the neck at the lower end of the bowl 19' is suitably constricted so as properly to carry an external thread matching such internal thread, as shown at 38. The neck of the bowl 19' has extended through the same a port or passage 39 also of a diameter to have passed upwardly therethrough

the rod 21' as and for the purpose explained in connection with Figs. 1 to 4.

Referring to Figs. 6 and 7, the modification here shown is like that of Figs. 1-4, except that the bowl 40 is of metal and integral with the main structure corresponding to the structure 10. The same bit 20 is shown as present, as well as the same cap 22 and cup 23 and the same chain 25. The rod 21 carried by the cap 22 is for use as already described.

The bowl-liner 41, of porcelain, pottery or the like, has a bottom outwardly flaring skirt portion 42 for assisting to position the bowl-liner in the bowl 40 as illustrated. The bowl-liner 41 is held thus positioned by a removable metal ring 43 having three depending resilient tongues 44 snapped into interlock with an external peripheral bead 45 near the top of the bowl 40.

The bowl-liner 41 has a central bottom smoke-passing port 46 in alignment with the axis of a vertical channel 48 corresponding to the vertical channel of the main structure 10 and hence intersecting a horizontal channel corresponding to the channel 16.

A filter 47 of a suitable and preferably of a fibrous material, and desirably shaped as shown, that is, of slenderized frusto-conical form, is positioned in the vertical channel 48. The filter 47, as here illustrated, is of a height such that its top is at the bottom of the bowl-liner 41, with the bottom of the filter near the bottom of said vertical channel and abutting the cup 23. The top of the filter 47 is in intimate contact with the bowl-liner 41 and is concentric with the port 46.

As a result of this arrangement, a pipe is provided with an absolutely dry bowl.

Furthermore, the filter 47 is shaped to have a longitudinal bore 49, and a transverse bore 50 through which, with the filter properly angularly adjusted, the rod 21 normally extends. Should the port 46 become tobacco-clogged, the cap 22 may be removed, withdrawing the rod 21 from the filter and the main structure, and then, as in the case of the combination of Figs. 1-3, after detachment of the cup 23, the rod 21 may be passed upward through the main structure (in the present case, by way of the bore 49 through the filter), for passage through the port 46, as indicated in dot and dash lines in Fig. 6, to clear said port.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I

claim as new, and desire to secure by United States Letters Patent is:

A smoking pipe comprising a main structure cruciform in side elevation, said structure having a horizontal channel from end to end providing a hollow forward extension and a hollow rearward extension and a vertical channel intersecting said horizontal channel intermediate of its ends providing a hollow upward extension and a hollow depending extension, a bowl extending upwardly from said upward extension, a bit detachably connected to said forward extension, a bowl-liner mounted in said bowl and having a bottom port aligned with said vertical channel, a detachable closure for the rear end of said rearward extension, a detachable closure for the bottom of said depending extension, a rod-like member projected from the first-named closure into said horizontal channel, so constructed and arranged that when the pipe is smoked with both closures in place said rod-like member functions for the accumulation of viscous matters and the like and the second-named closure functions for saliva trapping; and when said port of said bowl-liner is tobacco-choked, said rod-like member following removal of said closures, may be inserted upward through said vertical channel and then upward through said port to clear said port, and an elongated removable filter in said vertical channel with its length extended vertically for placement of the top of said filter against the bottom of said bowl-liner in concentric alignment with said port with the bottom of said filter in the bottom of said vertical channel, abutting said second closure, said filter being of a nature to allow passage therethrough of said rod either lengthwise or laterally thereof.

OSCAR STEIN.
